VENTILATING AND CIRCULATING SYSTEM

James B. Shaver, Cleveland, Ohio

Application October 24, 1939, Serial No. 300,977

5 Claims. (Cl. 98—38)

This invention relates to ventilating and circulating systems.

An object of the invention is to provide an improved system or method of air distribution.

Another object is to provide an improved apparatus which will distribute air.

Another object is to provide an improved apparatus which will distribute air throughout large spaces.

Another object is to provide an improved apparatus which is capable of handling large volumes of air in short periods.

Another object is to provide an improved apparatus which will effectively clean the air handled.

Another object is to provide an improved apparatus which will be simple in construction.

Another object is to provide an improved apparatus which will be efficient in operation.

Another object is to provide an improved apparatus in which parts will be easily accessible.

Another object is to provide an improved apparatus which will be compact.

Another object is to provide an improved apparatus which may be easily installed.

Another object is to provide an improved apparatus in which the air supply may be varied at will.

Another object is to provide an improved apparatus which may be economically produced.

Another object is to provide an improved apparatus which may be economically operated.

Other objects will hereinafter appear.

The invention will be better understood from the description of one practical embodiment thereof, illustrated in the accompanying drawing, in which:

Figure 1 is a vertical sectional view of a room ventilated in accordance with the system of the present invention;

Figure 2 is a side elevational view, partly broken away and shown in section, to an enlarged scale, of the ventilating and circulating apparatus shown in Figure 1;

Figure 3 is a perspective view of the apparatus of Figure 2, to a somewhat reduced scale, showing the side of the apparatus appearing at the left in Figure 2; and

Figure 4 is a view similar to Figure 3, taken in the opposite direction therefrom.

Ventilating systems heretofore have quite customarily been caused to deliver air to rooms, generally by blowing it into the rooms, and it has, of course, been common practice to install electric fans which agitate the air within a room.

While such means have obtained circulation in a measure, we all know that they are inadequate during the periods when circulation and ventilation is most required, as in the hotter days of summer, and, likewise in the colder days of winter when the proper distribution of heated air is necessary.

According to the system of the present invention, air is not merely pumped into a room, nor blown about promiscuously within this space, but certain definite currents are established, these being related to a main current or stream of a large volume of air moving at relatively high velocity and traveling well over the heads of 10 the occupants of the room. This current conveniently is caused to travel adjacent to the ceiling.

An induced current, having the same volume of air, but of greater cross-section and so moving at much reduced velocity, returns along the lower part of the room, and air from the high speed main current moving out laterally and descending throughout the main volume of the room, reaches every part of it.

20 To achieve this result, it is necessary to project the high velocity current in a fairly compact and well defined stream in a direction which will cause it to pass with relatively little turbulence, being clear of obstructions or of impinging abruptly on surfaces until it reaches the far end of the room.

25 Of course, some eddies will be formed at the sides of and underneath the main stream, and these will abstract or divert quantities of air 30 as the stream passes along, but some portion of the high velocity stream continues on its course substantially to the wall remote from the circulating apparatus, in order that the entire body of air within the room may be moved.

35 This is illustrated somewhat diagrammatically in Figure 1, in which the circulating apparatus is indicated generally at 1, this being mounted in alignment with the closed position of the upper sash 2 of a window. The window also includes a lower sash 3 and frame 4 set into a wall 5.

40 The circulating apparatus is, therefore, in the upper portion of the room, but not immediately adjacent the ceiling 6.

45 It is arranged to project air by means of circulating apparatus and directing vanes or the like, which will be described hereinafter, in an upwardly direction toward the ceiling, but not in such a direction that it will strike the ceiling so abruptly as to create turbulence.

50 The stream 7, when it reaches the ceiling,

therefore, continues along in contact therewith, as indicated generally by the arrows 8 in Figure 1, throughout its course. This stream is above the normal headspace of the room, so that occupants are not subjected to discomfort from the rapidly moving current. Some of the air of the stream is separated therefrom by eddy currents and friction with surrounding air, falling toward the floor and spreading toward the sides, while the air which reaches the remote wall passes down along this wall, probably with some little turbulence at this point, due to its right angle change in course.

Air for re-circulation returns to the circulating apparatus, as indicated by the arrows 9 in the part of the figure, while fresh air from the outside may be drawn in the manner indicated by the arrows 10.

The circulating apparatus consists of a supporting frame comprising a rectangular plate 11, shown as supported on a Z-bar 12 adapted to be connected to the window frame, the plate being reinforced by two metallic angles 13.

The plate is cut away to provide a circular opening 14, the central portion of which is covered by a smaller circular plate 15 secured to the upright angles 13, while the space between the outer and inner plates is covered by a screen 16 such as of wire mesh.

Two horizontal channels 17 are secured to the angles, as by welding, and project inwardly, carrying at their inner ends a motor 18 provided with a fan or impeller 19.

Secured to the plate 11 and surrounding the circular opening is a cylindrical shell 20, provided in its cylindrical surface with a number of apertures 21.

The end of the shell remote from the plate is flanged inwardly, as indicated at 22.

Supporting arms 23 are secured to channels 17 and support a second cylindrical shell 24 of smaller diameter than and concentric with the first mentioned cylindrical shell 20. This shell terminates in an outwardly extending flange 25 in alignment with the flange 22 of the first mentioned shell, and at its other end terminates in a ring 26 supporting a plurality of transverse vanes or louvres 27 which direct the air upwardly.

An annular baffle 28 is carried by the interior of the second cylinder, approaching closely adjacent the tips of the impeller blades 19.

This baffle, together with the cylindrical casting 24, forms a kind of nozzle, concentrating the stream of air as it passes through the impeller, and causing it to move with substantially no internal turbulence in a relatively compact mass or stream. The inclination of vanes 27 is such that they direct this stream upwardly without noticeably agitating it.

A circular plate 29 having a concentric circular opening therethrough is arranged to overlie the space between flanges 22 and 25, and to it is secured a hollow cylindrical body 30 of filtering material, which may be metal mesh, mineral wool or other fibrous material, or any desired substance through which air may pass and which will remove dirt therefrom.

A cylindrical shutter 31 is arranged to be selectively moved to position covering or uncovering the openings 21, while the opening through plate 11 may be covered or uncovered by raising or lowering the window sash 2, so that air may be caused to enter the space between the shell and the filter cylinder either through the end

opening 14 of the device or through its side openings 21, or both, thus providing a simple control which will determine whether the air within the room be recirculated, whether this be replaced with air from the outside, or whether it be partly recirculated and partly replaced.

The disc 29 is held in place by readily detachable fastenings, such as wing nuts 32, turnbuckles, or the like, so that its filter 30 can be removed easily for cleaning or replacement without disturbing other parts of the apparatus.

It will be noted that the filter is on the intake side of the fan, and so does not in any way create turbulence in the stream of air discharged, or in any other way impair the efficiency of the fan.

The louvres, while directing the air upwardly, are set at a low angle of incidence to prevent their imparting so abrupt a change in direction as to cause turbulence of the air in any marked degree at this point.

If desired, heating and cooling elements may be included with the circulating apparatus shown which may be of any desired or well known type, such as coils of tubing, resistance wiring and the like, and therefore need no illustration.

If, because of the shape of the room, or for any other reason, it is desired to change the course of the main stream, a second circulating device, similar to that above described, may be positioned with its intake arranged to receive the main stream, and so that the second circulating device projects it in an altered direction. This device may correspond precisely to that above described, but it will be apparent that the need for the filter will be much less, and that this may be omitted without very noticeable results.

However, it is important that the air stream, upon such change in course, again be projected through a concentrating and directing outlet such as a Venturi-nozzle-like baffle 28.

A second circulating device may also be used, if desired, when extremely long spaces are to be ventilated, to pick up the stream, imparting additional force to it at an intermediate point.

While I have described the illustrated embodiment of my invention in some particularity, obviously many others will readily occur to those skilled in this art, and I do not therefore limit myself to the precise details shown and described herein, but claim as my invention all embodiments, variations and modifications coming within the scope of the appended claims.

I claim:

1. Ventilating apparatus comprising a tubular casing having an air inlet adjacent the periphery thereof and closed at its end adjacent and centrally with respect to said inlet, a tubular filter within the casing and spaced inwardly from said air inlet, an impeller having its intake arranged to draw air from within the filter, and driving means operably connected to said impeller.

2. Ventilating apparatus comprising a tubular casing having an air inlet adjacent the periphery thereof and closed at its end adjacent and centrally with respect to said inlet, a tubular filter within the casing and spaced inwardly from said air inlet, an impeller having its intake arranged to draw air from within the filter, a nozzle-like element concentrating the air delivered by said impeller, and driving means operably connected to said impeller.

3. Ventilating apparatus comprising a tubular casing, a tubular filter therein and concentric

therewith, the casing being provided with an inlet communicating with the space between the casing and filter, a closure preventing air entering the filter axially, an impeller mounted adjacent one end of the casing, a cylindrical casing surrounding the impeller and concentric with the first mentioned casing and spaced inwardly of the filter, and driving means connected to the impeller.

4. Ventilating apparatus comprising a tubular casing, a tubular filter therein and concentric therewith, the casing being provided with an inlet communicating with the space between the casing and filter, a closure preventing air entering the filter axially, an impeller mounted adjacent one end of the casing, a cylindrical casing surrounding the impeller and concentric with the first mentioned casing and spaced inwardly of the filter, and driving means connected to the

impeller, the filter being detachably secured in place and removable bodily and axially over the last mentioned casing.

5. Ventilating apparatus comprising a tubular casing, a tubular filter therein and concentric therewith, the casing being provided with an inlet communicating with the space between the casing and filter, a closure preventing air entering the filter axially, an impeller mounted adjacent one end of the casing, a cylindrical casing surrounding the impeller and concentric with the first mentioned casing and spaced inwardly of the filter, driving means connected to the impeller, the filter being detachably secured in place and removable bodily and axially over the last mentioned casing, and means controlling said inlet to the first mentioned casing.

JAMES B. SHAVER.
